UNITED STATES PATENT OFFICE

131,103

DESIGN FOR A DOMESTIC REFRIGERATOR

Harold L. van Doren, Toledo, Ohio, assignor to
Philco Corporation, Philadelphia, Pa., a corpora-
tion of Pennsylvania

Application June 12, 1941, Serial No. 101,432

Term of patent 14 years

To all whom it may concern:

Be it known that I, Harold L. van Doren, a citizen of the United States, residing in Toledo, county of Lucas, State of Ohio, have invented a new, original, and ornamental Design for a Domestic Refrigerator, of which the following is a specification, reference being had to the accompanying drawings, forming part thereof, in which:

Figure 1 is a front perspective view of a domestic refrigerator, with the outer door open, showing my new design; and

Figure 2 is a like view in front perspective, showing the refrigerator with its inner door, crisper and vegetable bin, respectively, in open condition for access.

The characteristic features of the design reside in those portions shown in solid lines.

I claim:

The ornamental design for a domestic refrigerator, substantially as shown and described.

HAROLD L. VAN DOREN.
